UNITED STATES PATENT OFFICE.

HIRAM H. WARD, OF PACKWAUKEE, WISCONSIN, ASSIGNOR OF ONE-HALF
TO JOHN H. COON, OF SAME PLACE.

BURGLAR-ALARM.

SPECIFICATION forming part of Letters Patent No. 249,430, dated November 8, 1881.

Application filed March 26, 1881. (Model.)

To all whom it may concern:

Be it known that I, HIRAM HENRY WARD, of Packwaukee, in the county of Marquette and State of Wisconsin, have invented a new and Improved Burglar-Alarm, of which the following is a specification.

The object of my invention is to provide a new and improved apparatus for giving an alarm in case any attempt is made to open a door or window to which the alarm is attached, or when the alarm itself is being tampered with.

The invention consists in a guard for a door or window formed of a cord or wire that is alternately passed over rollers on a bar rigidly attached to one side of the casing of the door or window and over rollers on a movable bar held by staples to the opposite side of the casing, so that the cord or wire crosses the opening of the door or window casing several times, which movable bar is connected by cords or wires with a pivoted rod or lever, which is turned or tilted by springs acting upon it as soon as the cords connecting with the movable bar on the window-casing are cut or strained, thus causing cams on this lever to raise another lever, whereby a ratchet-wheel acted upon by a clock spring or weight is released and rotated and vibrates a hammer that strikes a gong.

In the accompanying drawings, Figure 1 is a front elevation of my improved burglar-alarm, showing the manner in which it is attached. Fig. 2 is a longitudinal elevation of the lever connected by cords or wires with the movable bar of the guard. Fig. 3 is a plan view of this lever and the lever for releasing the ratchet-wheel for operating the alarm-bell. Fig. 4 is a longitudinal elevation of the lever for holding the ratchet-wheel. Fig. 5 is a detail perspective view of the staple for holding the movable bar of the guard. Fig. 6 is a perspective view of a pulley for the cord or wire passing from the movable bar of the guard to the lever acting upon the lever holding the ratchet-wheel.

Similar letters of reference indicate corresponding parts.

A bar, A, provided with a series of rollers,

B, or apertures, is rigidly attached to one side 50 of the casing C of a window or door, and a bar, D, also provided with rollers B or apertures, is loosely held to the opposite side or post of the casing by two longitudinally-slotted staples, E, the slot of which is longer than the 55 width of the bar D, so that this bar can move in these staples in the direction of the length of their slots. A cord or wire, F, is attached to the upper end of the bar D, passes over the top roller, B, of the bar A, back to the bar D, 60 and so on, and the end of the same is fastened to the bottom of the bar D. The lower end of this bar D is connected by a wire or cord, G, with one end of a lever, H, which turns on its axis in bearings J of a plate, K, which is pivoted on a suitable plate, I, to permit a swinging movement of this lever H in the plane parallel to that of the plate K. The lever H is provided with a bend, L, and the end of the lever H beyond this bend L is connected with 65 the movable bar D by a cord or wire, M, which only passes through an eye in the end of the lever H, and is secured to the end of a bent lever, N, pivoted to the lever H near the top of the bend, so that the short inner arm of 70 this bent lever N will pass a short distance along the bend L of the lever H, as shown in Fig. 2. A spiral spring, O, is secured to the lever H, is coiled around it, and is also secured to the plate K, and has the tendency to 75 turn this lever in such a manner that the bend will be in a horizontal position. A spring, P, with a shoulder, P', at the end, is secured to the plate K, and serves to hold the bent part of the lever H raised. A spiral spring, Q, is 80 attached to the base-plate I and to the lower end of the lever H, and turns this end of this lever and the plate K in a direction from the movable bar D of the guard-frame. A beveled cam, R, is fastened to the edge of the plate K, 85 and a projecting cam, S, is fastened to the lever H, this cam S being horizontal when the bent part of the lever H is upright. The outer end of a lever, T, rests upon the above-mentioned cams, whereas the inner end is pressed 90 upward by a spring, U, and catches a stud, V, on the under side of a ratchet-wheel, W, which is acted upon by a clock-spring, X, or a weight, 95

which ratchet-wheel oscillates an anchor, Y, and the hammer Z attached thereto when it is rotated by the spring X or weight, and thus causes the hammer Z to strike the bell or gong 5 A' repeatedly and give the alarm. If the cord or wires M and G must be passed around a corner they are passed over a pulley, B', as shown in Fig. 6.

The operation is as follows: The lever H is 10 turned upward and held in this position by the spring P. The rope or cord F is then drawn taut, so as to overcome the action of the spring Q and hold the inner edge of the bar D against the inner end of the slot of the lower staple E, 15 whereas the outer edge of the bar D rests against the outer end of the slot of the upper staple E, as shown in Fig. 1, the cords or wire M and G being drawn taut. If a person attempts to pass through the door or window he 20 will come in contact with the cords or wires F, and will stretch the same, thus drawing the upper end of the bar D, and consequently the wire M also, in the direction of the arrow a', whereby the outer end of the bent lever N is 25 drawn downward, and the short end of this lever pushes the spring P off of the lever H and releases the same. The spring O will now rotate the lever on its axis, as indicated in dotted lines in Figs. 1 and 2. The cam S raises 30 the outer end of the lever T, thereby overcoming the spring U and depressing the inner end of the lever T and releasing the wheel W, which is rotated by the spring X and oscillates the hammer—that is, the alarm is sounded; but if a burglar discovers the wires or cords 35 F and does not press against them, but cuts the cords M and G in order to be able to remove the guard, the spring Q acts upon the lower end of the lever H and turns the same 40 in the manner indicated by the arrow b'. The beveled cam R raises the outer end of the lever T and sounds the alarm in the manner described above. The alarm may be any desired distance from the door or window, but is preferably arranged as near it as possible. 45

I am aware that it is not new to use a wire frame covering a door or window, and so connected to an alarm that entry cannot be effected without a great deal of noise; but 50 What I claim as new and of my invention is—

1. In a burglar-alarm, the combination, with a door or window casing, of the fixed bar A or equivalent, the movable bar D, the cord or wire F, passing from one bar to the other, and of an alarm apparatus connected with the movable bar, substantially as herein shown and described, and for the purpose set forth. 55

2. In a burglar-alarm, the combination, with the movable bar D of a guard placed across the window, of the cord or wire M, the bent lever H, the bent lever N, the spring-catch P, the spring O, the cam S, the lever T, and a spring ringing apparatus held by the lever T, substantially as herein shown and described, 60 65 and for the purpose set forth.

3. In a burglar-alarm, the combination, with the bent lever H, of the bent lever N, pivoted thereto, the spring-latch P, and the cord M, passing through an eye in the end of the lever H 70 and secured to the end of the lever N, substantially as herein shown and described, and for the purpose of releasing the lever H from the spring-catch P, as set forth.

4. In a burglar-alarm, the combination, with the movable bar of a guard placed over the window, of the cords M and G, the lever H, pivoted in a pivoted plate, K, of a lever, T, and spring bell-ringing apparatus, substantially as herein shown and described, and for the purpose set forth. 80

5. In a burglar-alarm, the combination, with the movable bar D of a window-guard, of the cord or wire G, the lever H, pivoted to a pivoted plate, K, the beveled cam R, the spring 85 Q, the lever T, and a spring bell-ringing apparatus, substantially as herein shown and described, and for the purpose set forth.

6. In a burglar-alarm, the combination, with the movable rail D of a guard placed over the window, of the cords M and G, the levers H and N, the springs O and Q, the pivoted plate K, the cams R and S, the lever T, and a spring bell-ringing apparatus, substantially as herein shown and described, and for the purpose set 90 95 forth.

HIRAM HENRY WARD.
